UNITED STATES PATENT OFFICE

CHARLES ANDREW HISLOP, OF SEAMILL, WEST KILBRIDE, SCOTLAND, ASSIGNOR TO
IMPERIAL CHEMICAL INDUSTRIES, LIMITED, A CORPORATION OF GREAT BRITAIN

SHOTGUN CARTRIDGE

Application filed July 7, 1932, Serial No. 621,277, and in Great Britain July 7, 1931.

This invention relates to improved shot gun cartridges, and has for its principal object the provision of a new and improved form of shot gun cartridge wad.

5 Hitherto the wads for shot gun cartridges have consisted of solid cylinders of felt, cork or other similar material, although various forms of hollow wads have also been proposed.

10 According to the present invention a shot gun cartridge is provided with a wad consisting of a unit formed from two hollow substantially cylindrical cups, open at one end and closed at the other, the cups being 15 of slightly different diameters, and the one cup being inverted inside the other and preferably fitting closely therein, and the resulting wad being so arranged or constructed that the powder gases may have access to its 20 interior when the cartridge is fired, and the overpowder card, if such is used, being perforated or considerably reduced in thickness so as to be easily ruptured by the powder gases.

25 The cups are made of any suitable material such as moderately stiff paper, cardboard, millboard, compressed fibre, or the like, which is sufficiently deformable for the purpose of providing the necessary obturation in the barrel of the gun. The cups are conveniently pressed out of circular pieces of the material by means of dies, and the edges may be trimmed. If desired the cups may be lubricated by dipping them in paraffin wax.

30 When the wad is placed in the cartridge with the mouth of the larger cup facing the powder, the usual overpowder card is preferably dispensed with, or is perforated or considerably reduced in thickness so that it 35 will be easily ruptured by the powder gases.

40 The powder gases will then find their way into the interior of the wad via the narrow clearance between the walls of the respective cups, and the internal pressure will tend to force the walls outwardly at the same time 45 as the wad is driven forwardly; thus producing the desired obturation. On the other hand, if the wad is placed in the cartridge in the reverse position, i.e. with the base of 50 the larger cup facing the powder, an entry into the wad must be provided for the gases by perforating the base of the larger cup, preferably by cutting two intersecting slits 55 therein. As before, the overpowder card is preferably dispensed with, or is perforated

or considerably reduced in thickness so that it will be ruptured by the gases.

In practice, it may not be convenient to arrange the wad in any one particular direction and therefore it is preferable in all cases 60 to perforate the base of the larger cup as mentioned, since if this is done the gases will be able to enter the wad whichever end is presented towards the powder. The base of the smaller cup may also be perforated, but 65 this is not essential since as stated above the gases already have a means of entry via the narrow clearance between the walls of the cups. If the perforations in the wad or overpowder card, if such is used, are more 70 than slits care must be taken that powder cannot fall into the interior of the wad, and a thin paper membrane may be interposed which if desired may be gummed to the base 75 of the wad or the overpowder disc.

The invention is illustrated in the accompanying drawing, in which Figures 1 and 2 are diagrammatic sections of a complete cartridge showing the wad in the two alternative positions, and Figure 3 is an end view of the 80 wad showing the perforations in the base of the larger cup. Referring to Figures 1 and 2, 1 is the cartridge case, 2 the metal base cap, 3 the percussion cap, and 4 the base wad. 5 is the powder charge, 6 the shot charge, 7 the 85 undershot card, and 8 the overshot card or closing disc. The wad consists of two cylindrical cups 9 and 10, pressed for example out of Kraft pulp board. In the form illustrated the inner cup is a friction fit in the 90 outer cup and the outer cup is a friction fit in the cartridge case, the clearances having been exaggerated in the drawing.

95 Referring to Figure 3, the outer circle 10 denotes the base of the larger cup and the dotted inner circles denote the rim of the open end of the inner cup immediately below the base of the larger cup. Two intersecting slits 11 are cut in the base of the larger cup. These slits need not penetrate through the 100 base as it is only necessary to weaken the base of the cup to such an extent that it will be easily ruptured by the powder gases when placed in the position of Figure 2. As will be seen from Figures 1 and 2, no overpowder 105 card is provided, but of course one may be inserted if desired subject to the precautions mentioned above.

When, according to our invention, the above described cup wad is substituted for 110

the normal felt wad, equivalent ballistics can be obtained with reduced powder charges, and the recoil is also substantially reduced. This is shown by the following tests made with 12-bore cartridges.

Test 1

18. The wad consisted of two flat bottomed cylindrical cups open at one end and closed at the other, which were pressed from compressed paper board 0.028" thick. The smaller cup was a friction fit in the larger cup, and the outer diameter of the wad was about 0.738" and the depth about $\frac{9}{16}$ ". The base of the larger cup was provided with two short intersecting slits as shown in Figure 3. The wad was placed in the cartridge in either of the positions shown in Figures 1 and 2, directly over the powder without using an overpowder card. The powder charge was 30 grains of smokeless diamond powder. The undershot card was $\frac{11}{16}$ " thick and the shot charge consisted of $1\frac{1}{16}$ oz. of No. 6 shot.
25. The pressure measured 1" up the barrel of the gun, on firing, was 2.84 tons per sq. in., the recoil measured 9.46" and the velocity over 20 yards of the shot was 1091 feet per second.
30. In a comparative test with a 12-bore cartridge having a powder charge of 33 grains of the same powder, an overpowder card $\frac{11}{16}$ " in thickness, a felt wad $\frac{7}{16}$ " in thickness and an undershot card $\frac{5}{16}$ " in thickness, and the same shot charge, the pressure was 2.93 tons per sq. inch, the recoil 9.69 inches and the velocity over 20 yards 1082 feet per second.

Test 2

40. The powder charge was 30 grains of Nobel 48 powder. No overpowder card was used. The cup wad was exactly similar to that used in Test 1 and the undershot card and the shot charge were also the same as in Test 1. The pressure 1" up the barrel was 3.06 tons per sq. inch, the recoil 9.32 inches, and the velocity over 20 yards 1062 feet per second.

In a comparative test with 33 grains of the same powder, a $\frac{11}{16}$ " overpowder card, a $\frac{7}{16}$ " felt wad, a $\frac{11}{16}$ " undershot card and a $1\frac{1}{16}$ oz. charge of No. 6 shot, the pressure was 3.11 tons per sq. inch, the recoil 9.68 inches, and the velocity over 20 yards 1062 feet per second.

As many apparently widely different embodiments of this invention may be made without departing from the spirit and scope thereof, it is to be understood that we do not limit ourselves to the specific embodiments thereof except as defined in the appended claims.

I claim:

1. A shot gun cartridge comprising a pow-

der charge and a shot charge and an intermediate wad consisting of a unit formed from two hollow substantially cylindrical cups which are open at one end and closed at the other end, the said cups being of slightly different diameters and the cup of smaller diameter being inverted inside the other cup.

2. A shot gun cartridge as claimed in claim 1, in which the wad is placed directly over the powder charge (without employing the usual over-powder card) with the open end of the larger cup facing the powder, thereby providing access for the powder gases to the interior of the wad when the cartridge is fired.

3. A shot gun cartridge as claimed in claim 1, in which the wad is placed directly over the powder charge (without employing the usual over-powder card) with the closed end of the larger cup facing the powder, said closed end being adapted to allow the passage of the powder gases into the interior of the wad when the cartridge is fired.

4. A shot gun cartridge as claimed in claim 1, in which the wad is placed directly over the powder charge (without employing the usual over-powder card) with the closed end of the larger cup facing the powder, said closed end being perforated by means of intersecting slits which do not permit any powder to fall into the wad.

5. A shot gun cartridge comprising a powder charge and a shot charge and an intermediate wad consisting of a unit formed from two hollow substantially cylindrical cups which are open at one end and closed at the other end, the said cups being of slightly different diameters and the cup of smaller diameter being inverted inside the other cup, the said wad being separated from the powder charge by an over-powder disc which is adapted to allow the passage of the powder gases into the interior of the wad when the cartridge is fired.

6. A shot gun cartridge as claimed in claim 5, in which the open end of the larger cup faces the powder.

7. A shot gun cartridge as claimed in claim 5, in which the closed end of the outer cup faces the powder and is adapted to allow the passage of the powder gases into the interior of the wad when the cartridge is fired.

8. A wad for shot gun cartridges consisting of two hollow cups made of material of the kind typified by cardboard, the said cups being of slightly different diameters and the cup of smaller diameter being inverted inside the other cup, the base of which is slit to allow the passage of powder gases into the interior of the wad when the cartridge is fired.

In testimony whereof I hereunto affix my signature.

CHARLES ANDREW HISLOP.
